EXERCISING APPARATUS

Filed Feb. 21, 1927

INVENTOR:
Rudolph Blank
BY
Edward S. Higgins
his ATTORNEY

UNITED STATES PATENT OFFICE

RUDOLPH BLANK, OF EMERSON, NEW JERSEY, ASSIGNOR TO ANNA MARIE BLANK, NEE LECHNER, OF EMERSON, NEW JERSEY

EXERCISING APPARATUS

Application filed February 21, 1927. Serial No. 169,995.

This invention relates generally to exercising apparatus and more particularly to apparatus of a new type for developing and strengthening the muscles of the chest, back, neck, shoulders, arms, and legs.

In the types of apparatus now on the market, which use the principle of extending resilient parts, in order to develop the muscles of a certain part of the body, for instance the chest or the biceps, it is usually necessary to hold them at a certain height and face a certain way, whereas in order to develop the muscles of another part of the body, say the back, or the complementary muscle of the same set, say the triceps, it is necessary to hold the apparatus at a different position or turn around and face a different way. These types limit the development of strength essentially to those muscles which are used principally in pulling a resisting part of the apparatus, that is, they bring into play only certain muscles, neglecting certain other muscles which are only brought into play by a pushing motion.

It is a primary object of my invention to provide an apparatus that will afford both a push and a pull action. This combining of the pushing and pulling features doubles the effect of muscular development by simple correlated back and forth movements.

Another object is to provide an apparatus that affords a maximum of action to the muscles by a minimum expenditure of energy.

Still another object is to provide an apparatus that can readily be collapsed and formed into a compact structure for convenience in shipping and carrying.

A still further object is to provide an apparatus that is simple in construction, cheap to manufacture and durable and convenient in use and provided with interchangeable parts to lessen or increase the tension when desired.

Other objects and advantages of my improved apparatus will appear from the description to follow, taken in connection with the drawing forming a part thereof, in which—

Figure 1 is a plan view of the preferred

form of my improved apparatus, parts being shown in section.

Figure 2 is a sectional view of the form shown in Figure 1 looking in the direction indicated by the arrows 2—2.

Figure 3 is a detail view of one of the handles.

Figure 4 is a detail view showing the mounting of the spiral springs.

Referring to the drawing and Figure 1 in particular, the improved apparatus comprises a pair of elongated members, such as the complementary frame members 10 and 11, of substantially equal length formed of metal, preferably of stout wire or any other suitable material. Each of said frames is rectangular in shape and is illustrated as being of a unitary structure, but it will be understood the frames may be made sectional. It will be noted that the frame 10 is somewhat wider than the frame 11, permitting the latter frame to slide inside of the former, but it will be understood that instead of making one of said frames adapted to slide within the other, the two frames may be made of the same width and side members of said frames slide upon or within one another. The frames 10 and 11 each consists of a single piece of wire or other suitable material and which is circled at one end to form a loop or eye 12 at one side thereof and also circled at the opposite side of the same end to form another lateral loop 13 instead of making these frames of a single piece of wire, they may be made of more than one piece. Mounted loosely on the end cross piece of the frame 10 is a wooden handle 14 and similarly mounted on the end cross piece of the frame 11 is a wooden handle 15. It will be noted from Figure 2 that these handles have a flat surface and rounded edges for a purpose which will be explained hereinafter.

Mounted loosely on the side members of the frame 10 is an intermediate wooden handle 16 and mounted loosely on the side members of the frame 11 is another such wooden handle 17, which handles 16 and 17 are shaped similarly to the handles 14 and 15, and by reason of the loose mounting thereof said handles 16 and 17 may slide along the frames

10 and 11, respectively. Each of said handles is provided with an opening 18 and each of said openings 18 is slightly greater in diameter than the diameter of the metal forming the frames 10 and 11 in order to permit said handles 16 and 17 to slide longitudinally of the frames. Formed adjacent each end of said handles 16 and 17 is a grooved portion 19.

10 Detachably secured to each of said frames 16 and 17 is a bail 20 formed of metal or any other suitable material. Mounted on the outside ends of each of said bails 20 by welding or riveting or in any suitable manner is a 15 spring clip 21. Said clips 21 are formed of metal which is adapted to flex and are about as wide as the grooved portion 19 of the handles 16 and 17 and when in operative position as illustrated in Figure 1 are adapted to fit snugly in said grooved portions. Instead of separate clips mounted on the bails, 20 the bails may be made of flexible metal and their ends formed with loops having opened ends for engagement with the handles. 25 Formed on the cross piece of each of said bails 20 is a plurality of eyelets 22, three of such eyelets being illustrated as formed integrally on each bail, but it will be understood that any desired number may be used and that 30 instead of forming said eyelets integrally with the bail they may be separately mounted thereon. Mounted on said eyelets and passing between said bails 20 are a plurality of spiral springs 23, three of such springs being 35 shown in the drawing. It will of course be understood that a single spiral spring 23 or any desired number, depending upon the tension desired, may be used, the greater the number of said springs, the greater the tension. It will also be understood that instead 40 of spiral springs, elastic bands or any elastic or resilient material may be used. As will be seen from Figure 1, the cross piece of the bail 20 is sufficiently removed from the handles 16 and 17 to permit the hand of the user 45 to freely grasp said handles. As will be apparent from Figure 2, the frames 10 and 11, bails 20 and spiral springs 23 are all in the same plane thereby permitting said apparatus to rest flat on its support and making it 50 convenient to pack and carry the same.

In using the device shown in Figure 1, the operator grasps the handles 14 and 15 and pushes said handles towards each other, 55 which push is resisted by the spiral springs 23. When the loops 12 and 13 come into contact with the handle 16 and 17, said handles are pushed outwardly along the frames until they come within the grasp of the operator. The operator then grasps the 60 handles 16 and 17 and pulls outwardly, which outward pull is resisted by the same spiral springs 23. The shape of the handles readily permits the operator to hold both adjacent handles in one hand.

In order to exercise the legs, stand the device in a vertical position on the floor, grasp the upper handle of the frame on the floor by the hand and move the other frame by the foot up and down.

70 While I have described only one embodiment of my invention, it will be understood that various changes may be made in the form of the parts and it is desired to be limited only by the state of the prior art 75 and the appended claims.

I claim:

1. An exercising apparatus comprising a pair of frames positioned one within the other and slidably along each other, loops 80 formed on the inner ends of each of said frames the loops of one frame adapted to encircle the other frame, a handle fixedly mounted on the outer end of each of said frames, a second handle slidably mounted 85 on each of said frames, a bail detachably mounted on each of said slidable handles and spiral springs detachably mounted on said bails and passing therebetween.

2. An exercising apparatus comprising a 90 pair of frames slidable along each other, each of said frames having outer and inner grip members, said outer grip members being movable relative to each other and relative to the inner grip members of the respective opposite frames, said inner grip members being movable relative to each other and relative to the outer grip members of the respective opposite frames, resilient means attached to and passing between said frames. 100

3. An exercising apparatus comprising a pair of frames arranged parallel to and slidably along each other, each of said frames having both an outer grip member and a 105 slidable inner grip member arranged thereon, all grip members being movable relative to each other, resilient means attached to and passing between said frames.

4. An exercising apparatus comprising a pair of elongated and substantially equally 110 long members arranged parallel to each other, each member being provided with laterally disposed eyes and holding the other member slidably arranged therein, a grip member arranged at each of the outer ends of the two 115 elongated members, an intermediate grip member slidably arranged on each elongated member between its outer grip member and the eyes of the other elongated member, and resilient means arranged between and freely suspended from said intermediate grip members. 120

5. An exercising apparatus comprising a pair of oppositely inversely arranged frames, each frame having substantially equally 125 long and parallel members connected by a cross member and provided at their terminals with laterally disposed eyes, each eye holding a member of the other frame slidably arranged therein, a grip surrounding the cross 130

member of each frame, intermediate handles
slidably arranged on the parallel members
between the cross member of one and the eyes
of the other frame, a bail movably arranged
on each intermediate handle, and elastic
means detachably held by and between said
bails.

In testimony whereof I hereunto affix my
signature.

RUDOLPH BLANK.
